UNITED STATES PATENT OFFICE

ALFRED HERMANUZ AND KURT KLUG, OF KASSEL-WILHELMSHOHE, GERMANY, ASSIGNEES TO SCHMIDT'SCHE HEISSDAMPF-GESELLSCHAFT MIT BESCHRANKTER HAFTUNG, OF KASSEL-WILHELMSHOHE, GERMANY, A CORPORATION OF GERMANY

HIGH PRESSURE LOCOMOTIVE WITH INTERSTAGE SUPERHEATING

Application filed July 9, 1930, Serial No. 466,799, and in Germany August 31, 1929.

The object of this invention is a high-pressure compound locomotive with interstage superheating and especially a high-pressure locomotive having a comparatively short 5 smoke tube boiler located in the flow of the fire gases behind a directly or indirectly (e. g. by steam generated in a closed water tube system) heated high-pressure boiler, which generates the high-pressure working steam 10 of e. g. 50 to 100 atmospheres, the said fire tube boiler serving principally as feed water heater and mud collector for the high-pressure boiler and generating only a small quantity 15 of low pressure steam, which low pressure steam may be added to the exhaust of the high-pressure stage of the engine in an interstage superheater or may be used in auxiliary engines after being reheated in a small additional superheater.

20 To obtain high superheat on locomotives is materially more difficult than on stationary plants owing to the limited axle load and limited space on locomotives. To overcome those difficulties, the arrangement according to the 25 present invention is characterized by the fact that contrary to all previous smoke tube superheater arrangements for locomotives, the ratio of superheating surface and steam raising surface of the smoke tube boiler, which 30 ratio at present is always lower than 1 (one), is inverted and made higher than 1 (one). According to one form of the invention as shown in the drawings the flue tube boiler is fitted throughout or next to throughout with 35 smoke tubes containing more than four superheating tubes, the return bends lying as usual totally in these smoke tubes. Up to now such superheater arrangements, where all or nearly all smoke tubes are fitted with 40 superheater elements, have only been built as small tube or medium tube superheaters having two or at the most four superheater tubes in each smoke tube, while smoke tubes with more than four superheater tubes, 45 though already known, have only been built as so called large flue tube or "gross tube" superheaters with 2 to 4 rows of these "gross" tubes arranged above a plurality of empty narrow smoke tubes.

50 If, according to the invention, the flue or

smoke tube preheater of a high-pressure locomotive with interstage superheating, is built as a new type smoke tube boiler with large flue tubes each accommodating more than four superheater tubes, the uncommon condition mentioned above is arrived at, namely that in the flue tube boiler the ratio superheating surface to water heating surface becomes higher than 1 e. g. 1.5 with a high-pressure compound locomotive as shown in 55 the drawings and having the following characteristics: steam pressure in the high-pressure boiler 60 at., in the preheater boiler 14 at., temperature of the superheated high-pressure steam 450° C., temperature of the 60 superheated low-pressure steam 350° C.

The arrangement according to the invention has the important advantage that, though the preheater boiler extends with its water space a considerable part under the steam 70 and water drum of the high-pressure boiler, so ensuring a better support for the latter and increasing the stiffness of the whole aggregate, still a relatively small part of heat is absorbed at the expense of superheat by the increased water heating surface of the smoke tube boiler, for the water heating surface being relatively small in comparison with the superheating surface installed, owing to the use of large flue tubes with more than four 75 superheater tubes.

Further heat transmission to the superheater surface owing to the high velocity of the gases is very good from the outset and the large flue tubes can be rolled into the back boiler plate with reduced ends and it is possible to arrange behind this plate an accessible space for the cinders segregating from the slowing down flue gases, by leaving out some rows of high-pressure steam generating tubes, and this without affecting the superheat and without exposing the return bends in a higher degree to the danger of burning.

Referring to the accompanying drawings:—

Fig. 1 shows by way of example a longitudinal section through a locomotive, fitted with a superheater arrangement according to the invention,

Fig. 2 is a section on the line A—B in Fig. 1, and

Fig. 3 a section on the line C—D in Fig. 1, the frame and the driving gear being omitted.

Fig. 4 is a top plan view of a portion of the invention.

In the drawings 1 is the high-pressure water tube boiler which forms the fire box. 10 Adjoining this boiler in the flow of the combustion gases is located the preheater boiler 2. The preheater boiler is traversed by large section smoke tubes 3, each smoke tube accommodating six tubes of two superheaters 4 and 5, as shown on Fig. 2. A steam heated interstage superheater 6 serves for reheating the exhaust steam of the high-pressure cylinder 7, the cylinder being located in the example shown on the drawings on the centre line 20 of the engine. The high-pressure live steam passes through a pipe connection 81 connecting the outlet 8 of the boiler 1 with the inlet 9 of the saturated steam chamber of the high-pressure live steam superheater 4 and is highly superheated in the tubes of this superheater. Then the high-pressure steam passes through a pipe connection 10' connecting the outlet 10 of the superheated steam chamber with the inlet 11 of a heating coil or 30 element (not shown on the drawings) of the interstage superheater 6. After giving off its superheat the high-pressure steam flows from the outlet 12 through a pipe connection 12' to the inlet 14 of the saturated steam chamber 35 of a second flue tube superheater 5 acting as re-superheater and raising the high-pressure steam to the temperature wanted for the high-pressure stage of the engine. The high-pressure steam re-superheated passes from 40 the outlet 16 of the superheated steam chamber of the re-superheater 5 through a pipe connection 16' to the valve chest of the high-pressure cylinder 7. The exhaust steam from this cylinder enters the interstage superheater 6 by a pipe connection (not shown) 45 at the inlet 18 and passes superheated from the outlet 19 through a pipe connection (not shown) to the lateral low-pressure cylinders not shown on the drawings. The large flue tubes 3, accommodating each six superheater tubes, are reduced at the back end and rolled in as shown at 20. The steam generating pipes 22 of the water tube boiler, disposed across the flue in order to protect the smoke 50 tube superheaters against burning, are left out in front of the back end of the preheater boiler 2, giving free an accessible space 23 in which space cinders, owing to the reduction in the velocity of the gases, will deposit. 55 With this arrangement the water covered surface of each of the large tubes 3 of the preheater boiler 2 is considerably smaller than the steam touched surface of the six superheating tubes disposed in each flue tube. 60 65 The front return bends preferably do not ex-

tend to the front plate of the preheater boiler but have some distance from it, as possibly near the front plate of the preheater boiler the temperature difference between the gases and the superheated high-pressure steam becomes too small to add noticeably to the superheat. Under certain circumstances temperature difference might be nought or negative here and in this case the superheated steam conducting ends of the superheater tubes have to be covered with heat insulating material. The small quantity of low-pressure steam generated in the preheater boiler 2 may be drawn by a pipe connection 24 and supplied to the auxiliary engines (feed pump, air pump and the like) as saturated steam or superheated steam. In the latter case a small superheater could be located in the smoke box or the superheater tubes or this additional superheater could be arranged within one of the vertical rows of the large flue tubes of the preheater boiler 2. Alternatively the small quantity of low-pressure steam generated in the preheater boiler 2 may be led to the interstage superheater 6 and mixed with the exhaust of the high-pressure cylinder of the engine. In the example shown reheating is performed in a steam heated interstage superheater 6, but alternatively within the scope of the invention the exhaust steam of the high-pressure stage of the engine may be directly reheated in a flue tube superheater. In that case the interstage superheater 6 is omitted and in place of the secondary high-pressure superheater 5 a low-pressure flue tube superheater is located in the large flue tubes of the preheater boiler. In that case the exhaust steam of the high-pressure stage, considering the high temperature of the tube walls, has to be passed through an oil separator before entering the reheater.

While, in the form shown in the drawings, all of the superheater tubes terminate short of the fire box ends of the flue tubes, it is obvious that many of the same advantages will be gained as long as at least those superheater tubes which are arranged in the flue tubes, whose ends are located in the central or central and bottom portions of the space in the fire box end of the flue tube boiler occupied by the ends of the flue tubes, terminate short of the fire box ends of the tubes. In such a case it is still possible to maintain the free space 23 surrounded by walls and a roof of water tubes and in which cinders will deposit and to protect the ends of a majority of the superheater tubes, while keeping the flue tube boiler of large size.

What we claim is:

1. In a locomotive the combination of a water tube boiler forming the fire box and adapted to generate high-pressure steam, with a flue tube boiler adapted mainly to preheat the feed water of the said water tube boiler

- and provided with a plurality of flue tubes extending from the fire box superheating tubes of more than one flue gas heated steam superheater within said flue tubes and terminating short of the fire box ends thereof, the ratio of the flue gas touched heating surface of the superheaters to the water covered heating surface of the flue tube boiler being higher than 1 (one). 70
- 5 2. In a locomotive the combination of a water tube boiler forming the fire box and adapted to generate high-pressure steam, with a flue tube boiler adapted mainly to preheat the feed water of the said water tube boiler and provided with a plurality of flue tubes extending from the fire box superheating tubes of more than one flue gas heated steam superheater within said flue tubes and terminating short of the fire box ends thereof, the ratio of the flue gas touched heating surface of the superheaters to the water covered heating surface of the flue tube boiler being higher than 1 (one), each of said flue tubes containing more than 4 superheating tubes. 75
- 10 3. In a locomotive the combination of a water tube boiler forming the fire box and adapted to generate high-pressure steam, with a flue tube boiler adapted mainly to preheat the feed water of the said water tube boiler and provided with a plurality of flue tubes extending from the fire box superheating tubes of more than one flue gas heated steam superheater within said flue tubes and terminating short of the fire box ends thereof, the ratio of the flue gas touched heating surface of the superheaters to the water covered heating surface of the flue tube boiler being higher than 1 (one), each of said flue tubes containing more than 4 superheating tubes. 80
- 15 4. In a locomotive, the combination of a water tube boiler forming the fire box and adapted to generate high pressure steam, with a flue tube boiler adapted mainly to preheat the feed water of the said water tube boiler and provided with a plurality of flue tubes extending from the fire box superheating tubes of more than one flue gas heated steam superheater within said flue tubes, at least those superheating tubes in the flue tubes having their ends within the central and lower portions of said space terminating short of the fire box ends of the flue tubes, the flue gas touched heating surface of the superheating tubes being at least as great as the water covered heating surface of the flue tube boiler. 85
- 20 In testimony whereof we have affixed our signatures. 90
